SLIDING DOOR AND HARDWARE THEREFOR

Patrick Morgan Haley, Duluth, Minn., assignor to
Dowlong Manufacturing Co., Lafayette, Calif.,
a corporation of California

Application August 14, 1950, Serial No. 179,203

4 Claims. (Cl. 20—19)

1

This invention relates to an improvement in sliding doors.

One problem solved by the present invention is how to construct a fully removable sliding door. Heretofore sliding doors have been irremovable. Once they were installed they were there to stay. Subsequent adjustment could be made only by ripping out the wall to get at the machinery. If a roller jumped the track, as happened with some doors, or if a part wore out or sheared off, the wall had to be torn out to make repairs.

Another problem solved by the present invention is that of getting the door to hang straight so that it may move in its guides without any binding friction. Heretofore the brackets from which the cantilever arms were hung were liable to be installed on a slight tilt. This happened whenever the wood screw that held the bracket was put in slightly crooked. When the cantilever bars would hang at an angle from the bracket, they would bind against the guides, and the door became difficult to open and to close.

The present invention has solved these problems. The cantilever for its removable sliding door has a novel type of support member secured to the upper end of one of its cross-arms. This support member fits removably in a slot in a bracket that is secured to the wall inside the pocket at its innermost end. When the support member is lifted out of the slot, the door and its entire cantilever mechanism may be removed. A novel feature of the support member is that it includes a pair of eccentric bearings that are self-adjusting for positioning the door vertically, even when the bracket tilts.

Various objects and advantages of the invention will appear from the following description of a preferred embodiment. In accordance with United States revised statutes 4888, this embodiment is described in detail, but it is not intended thereby to narrowly limit the claims.

In the drawings:

Fig. 1 is a view in elevation of a door embodying the principles of my invention, most of the wall around one side of the pocket being removed to show the cantilever with more clarity. The removable jamb is also removed, and the door is shown in its installation or removal position. The dotted lines at the left of the figure show the cantilever and the edge of the door in its fully retracted position.

Fig. 2 is a view in section along the line 2—2 of Fig. 1. The removable jamb is shown in place, and the door is shown in its closed or extended position.

2

Fig. 3 is an enlarged fragmentary view in plan of the roller and its track at the lower left-hand corner of Fig. 1.

Fig. 4 is a view in perspective of the upper left hand portion of Fig. 1, showing the upper portion of one cross arm with its supporting bearing removed from the open-ended slot of the bracket which normally supports it.

Fig. 5 is a view in section of the bearing and bracket of Fig. 4, as it will appear when the bracket is installed in perfect vertical alignment.

Fig. 6 is a view in side elevation looking at Fig. 5 from the left.

Fig. 7 is a view in side elevation looking at Fig. 5 from the right.

Fig. 8 is a view in section similar to Fig. 5, but showing the bracket installed out of line but with the self-adjusting bearing in position to compensate for the misalignment so that the cantilever and the door hang vertically true.

Fig. 9 is a view in side elevation looking at Fig. 8 from the left.

Fig. 10 is a view in side elevation looking at Fig. 8 from the right.

Fig. 11 is an exploded view in perspective of the bearing that supports the cantilever bar.

Figs. 1 and 2 show a door 10 adapted to close an opening 11 or to retract into a pocket 12 between two walls 13 and 14, the walls being completed after the installation of the door. The door frame comprises a cripple 15 at the rear of the pocket 12, a jamb 16 across the opening 11 from the pocket 12, and a header 17 supported over the cripple 15 and jamb 16.

The jamb 16 includes a channel 20 covered over in the finished doorway by the removable stop member 21 (see Fig. 2). However, when the door is being installed, adjusted, or removed, the element 21 is left off or removed so that part of the door 10 can be slid over into the channel 20 (Fig. 1 and Fig. 2, dotted lines). In this position the rear edge 22 of the door 10 is out of the pocket 12 and is accessible for adjustment or removal. When the stop 21 is in place again the door does not move out far enough for the mechanism to show. This removable jamb thus makes possible adjustment of the door 10 after installation.

Preferably guides 25 are installed along the floor of the pocket 12, and similar guides 26 are provided beneath the header 17 in the pocket. The purpose of the guides 25 and 26 is to hold the door 10 to a straight path inside the pocket 12. Where there are vertical studs 27 in the pocket, the guides 25 and 26 are preferably located a short distance inside these studs, so that they

prevent the door from rubbing against the studs 27.

Runners or tracks are secured adjacent the lower ends of the cripple 15 and the rear edge 22 of the door 10. These runners or tracks may either comprise grooved channels 30 and 31, as shown in Fig. 1, or projecting rails 32, as shown in Fig. 3.

The cantilever comprises two crossed arms 35 and 36 pivoted at their center point on a bolt or stud 37. The arm 35 runs from the upper end of the cripple to the lower end of the door 10, and the arm 36 runs from the lower end of the cripple to the upper end of the door. At its upper end, the arm 36 is pivoted on a bolt or axle 38, which is held by a bracket 39, fixed to the side edge of the door 10 about 3 or 4 inches below the upper edge. This bracket 39 is disclosed and claimed in copending application No. 43,375, and makes possible both horizontal and vertical adjustment of the door 10 on the bar 36.

A bracket 40 is secured at a similar location near the upper end of the cripple 15. (See Figs. 4 to 10 for details.) The bracket 40 is U-shaped and has holes 41 in its back edge 42 where wood screws 43 may be used to secure it to the cripple 15. The upper edge of each of the side plates or arms 44 and 45 of the bracket is provided with a slot 46 which is preferably vertical and which opens through the said edge and is provided with an arcuate bearing surface 47 at its lower end.

The slot receives the cantilever-support bearing. This is mounted on a short shaft 50 having a knurled portion 51 located off-center (see Fig. 11). The bar 35 is perforated to receive the shaft 50 and engage on the knurled portion 51. Two bearing members 52 and 53 fit on the shaft 50 for free rotation on either side of the bar 35. Each member 52 and 53 is circular but is perforated at 54, considerably off center. Each member also has an inner flanged portion 56 and 57 and an outer bearing portion 58, 59. The outer bearing portion 58, 59 rests on the bearing openings 47. Keepers 55 are held in the grooves 55a adjacent the outer end of the shaft 50.

It is obvious that the support member can be removed from the bracket 40 by simply lifting the bar 35 until the support member is out of the slot 46. However, the eccentric bearings perform still another function. They correct for any inaccuracy in the installation of the bracket 40, as is shown in Figs. 8, 9, and 10. If the bracket 40 is tilted to one side or another, so that the door tends to bind against the guides 25, 26, the bearings 52, 53, being eccentrically mounted on the shaft 50, soon shift until the shaft 50 is horizontal and the door hangs vertically. They do this automatically, and so correct for any inaccuracy. The door 10 will then hang vertically, without any binding.

At the lower end of each of the arms 35 and 36 are rollers 60 and 61, which are adapted to roll along the tracks 30 and 31. The roller 60 and its track 30 should be proportioned so that the roller is confined laterally for a distance somewhat greater than the maximum vertical clearance of the door, so that it cannot jump the track. Once the angle of swing about the pivot point 47 is determined, the depth of the groove is determined by the proportions of the door. For example, the track 30 should be twice as deep as the possible vertical swing about the pivot point 38, where the distance from the roller 60 to the pivot point 38 is twice as great as the

distance from the pivot point 38 to the upper right hand corner of the door. Thus, if the track 30 is grooved (as in Figs. 2 and 5), the groove must be at least as deep as the maximum clearance of the door. If a grooved roller 62 as in Fig. 4 is used, its groove 63 should be correspondingly deep. The roller 61 and runner 31 may be the same as the roller 60 and the runner 30, but the grooves could be shallower.

To provide exact balance, so that the door will remain stationary in any position to which it is moved, there may be a hook 70 on the arm 35, a hook 71 on the door edge 22, and a spring 72 between them. By having a chain 73 on one end of the spring 72, the tension of the spring may be adjusted simply by inserting the proper link of the chain around the hook 71.

A door of this type can be moved with finger tip pressure. In order to prevent the rear edge of the door from banging against the cripple when the door is opened by too much force, a shock spring 75 may be placed adjacent the upper end of the door, to contact the cripple block 76.

It will be evident from the above description that even after the door is in place, it may be removed by removing the element 21 from the jamb and sliding the door 10 over into the channel 20. The bearing 52, 53 at the top of the bar may then be lifted out of the slot 46, and the entire door 10 and the cantilever may be removed, because the roller 60 is not restrained by the track 30. The cantilever may be restored by mating the rolling 60 in its track 30 and sliding the bearing 52, 53 in slot 46 of the bracket 40. If the bracket 40 is out of line, the cam shape of the bearings 52, 53 will soon adjust themselves so that the bar 35 hangs vertically. All that need be done is to move the door 10 back and forth a few times, and the cams will slide into their proper place.

I claim:

1. A removable sliding door combination of the type adapted to close an opening and to slide back into a pocket to open said opening, a normally-covered, recessed channel being provided on the opposite side of said opening from said pocket for receiving a portion of the door during adjustment or removal or installation, said door combination including a door; a cantilever supporting said door; a bracket installed in the interior end of said pocket, said bracket comprising a U-shaped channel member with a pair of aligned slots recessed from its upper end and terminating in an arcuate bearing surface; and a support member adapted to be secured to said cantilever and to fit in said slots, said support member including a pair of cylindrical flanged bearings having off-center openings therethrough and a shaft rotatable in said openings and secured to said cantilever, so that as said door is operated said cylindrical bearings tend to assume a position where said openings are horizontally aligned with each other thereby making said shaft horizontal so that said cantilever hangs vertically.

2. A removable sliding door including in combination, a door, adapted to close an opening and to slide back into a pocket to open said opening; a cantilever pivoted to said door and running on an open-track; a recessed channel provided on the opposite side of said opening from said pocket for receiving the door during adjustment or removal or installation; a removable stop member normally closing off said channel; a pair of rigidly supported generally vertical and laterally spaced parallel arms projecting into said pocket.

from the interior end thereof, said arms being provided with laterally aligned generally vertical slots having open upper ends and closed lower ends providing arcuate bearing surfaces; and a support member adapted to be secured to said cantilever and to fit removably in said slots, said support member including a pair of flanged cylinders having an off-center opening therethrough and a shaft secured to the cantilever and extending through said openings, so that upon continued operation the cylinders tend to assume a position in said bearings where the off-center openings become horizontally aligned.

3. Hardware for sliding doors of the cantilever type adapted to compensate for tilt in their installation so that the door will hang vertically true upon a pair of arcuate pivot bearings, comprising a pair of flanged cylinders having off-center openings therethrough, and a shaft rotatably supported in said openings and adapted to be secured to the cantilever, whereby said cylinders tend to assume a position on the bearings where the off-center openings lie along a horizontal axis.

4. Hardware for sliding doors of the cantilever type adapted to make the doors removable and to automatically correct any tilt brought about

by the installation of said hardware, including in combination a U-shaped bracket having a pair of generally vertical slots recessed into the upper edge of its extending parallel plates, the lower ends of said slots providing a pair of arcuate pivot bearings, a pair of flanged cylinders having off-center openings therethrough, and a shaft rotatably supported in said openings and adapted to be secured to the cantilever, whereby said cylinders tend to assume a position on the bearings where the off-center openings lie along a horizontal axis.
